UNITED STATES PATENT OFFICE.

WILLIAM E. S. STRONG, OF NEW YORK, N. Y., ASSIGNOR TO WILLIAM P. DEPPÉ, OF NEW YORK, N. Y.

CARBURETOR.

Application filed March 3, 1922. Serial No. 540,689.

My improvement relates more particularly to a carburetor provided with primary and secondary air conduits, and fuel nozzles, the mixture formed therein united in a common mixing chamber which is provided with a centrally opening throttle valve. A carburetor of this type is shown and described in a patent to William P. Deppé, No. 1,163,223 of December 7, 1915, and my invention relates to improvements, not only in the centrally opening throttle valve, but in other features of the carburetor.

One object of my improvement is to provide a centrally opening throttle valve, in which the valve members are balanced and this is accomplished by making the valve members cylindrical and providing each member with a cylindrical notch or recess, extending transversely of the respective cylinders and approximately to the axes thereof. The cylindrical members are provided with axial spindles and are mounted in parallel relation, so that adjacent surfaces are in contact, the valve being closed when the recesses are out of register.

The two cylindrical members of the valve are geared together to rotate in unison in opposite directions and the valve may be opened or closed by attaching the usual crank lever to the spindle of one of the cylindrical members.

Another object of my improvement is to form the cylindrical valve members and the trunnions thereof hollow or tubular, preferably made up of two similar sheet metal stampings, brazed or welded together to form a single unit. It is frequently desirable in utilizing low grade fuels in carburetors, to provide for heating the mixture at certain stages after it passes through the mixing chamber and in order that this may be satisfactorily accomplished, as the mixture leaves the carburetor, the hollow cylindrical valve members of my centrally opening throttle valve may preferably be supplied with exhaust gases from the engine, which, passing therethrough, will heat the valve members and particularly the surfaces exposed to the mixture passing therethrough

when the valve is partially open. Obviously, the amount and method of circulating the exhaust gases through the valve members may be varied according to the requirements of any particular lay-out or engine.

It is frequently desirable, particularly in carburetors for trucks to provide a second throttle valve, to be controlled automatically by a governor to thereby automatically limit the speed of the engine and, therefore, another object of my improvement is to show how two centrally opening throttle valves may be employed for this purpose. When two such throttle valves are employed, one of them will be connected for manual operation in the usual manner and the other connected for automatic operation by the governor, the arrangement being such that the governor throttle will be wide open when the engine is at rest and will be proportionately closed as the speed of the engine increases and approaches the predetermined maximum. Obviously, when a carburetor is provided with both the manual and governor operated throttles, one or both may be heated by passing exhaust gases through the hollow cylindrical throttle members, when such heated valves are desired or required in the operation of the engine.

In carburetors of this type, and particularly when used with low grade gasoline or fuel oils, it is desirable that all the air passed through the carburetor should be preheated, preferably from stoves or heaters surrounding the exhaust pipe. In this connection another object of my improvement is to provide for a single air inlet pipe for supplying heated air for both the primary and secondary air conduits. With this improved construction, uniformity in temperature of the air supplied to and passed through the respective conduits of the carburetor will be assured and the choke valve in the single air inlet pipe will be adapted to control the opening of the auxiliary valve by equalizing the vacuum pressure in the carburetor. In this manner I am enabled to simplify the mechanism by eliminating the

usual connection between the choke valve and the auxiliary valve.

Further it will be noted that in this manner of heating the throttle valve, the use of hollow cylindrical members, permits the largest possible area of metal exposed both to the heating fluid and to the fluids to be heated in a given space.

It permits the sections to be remote enough from the carbureting devices so as not to unduly heat the metals associated therewith, and cause boiling of the fuels in the supply bowl or the nozzles, which will result in irregular flow of the fuels, which irregularity will vary with the change of temperatures, throttle opening and engine speeds.

Furthermore, this improved construction of the throttle valve avoids sticking of parts such as would prevent proper operation, makes for light weight and low cost construction, and provides a regulated heat control of the throttle valve which cannot be obtained by electrical means.

In view of the fact that in actual operating conditions, a careful check up indicates that the throttle is wide open less than 10% of the total operating time, this construction of the throttle produces a sheeting effect on the stream of the mixture, with heat applied on both sides thereof, for the greater portion of the operating time, the sheeting and heating effect being greatest when most needed, that is, with smaller opening of the throttle, thus facilitating rapid vaporization and efficient operation.

Where the duplex throttle valves are used, one for the usual manual control operation and one to act as a governor valve, this construction affords two successive stages of heat application, with an intervening chamber permitting expansion and agitation of the mixture, thus effecting vaporization under equilibrium conditions instead of by fractional distillation.

It will be obvious that my improved carburetor may be provided not only with two centrally opening throttle valves for use on trucks but with a single centrally opening throttle valve when used on pleasure cars and the like, and both forms are represented in the accompanying drawings, in which Fig. 1 is a vertical section through the middle of the carburetor, transversely of the centrally opening throttle valves; Fig. 2 is a horizontal section on the line 2-2 of Fig. 1, indicating the construction and arrangement of the throttle valve members; Fig. 3 is a front elevation of the throttle valve portion of the carburetor, when provided with a single throttle valve.

Referring to the drawings, 1 is the float tank of the carburetor, which is connected through the tubular channel 2 with a vertically extending channel 3, the upper end of which is provided with the primary nozzle 4, as more particularly shown in Fig. 1 of the drawings. A branch channel 5 leads from the channel 3 into a vertical bore or channel 6, in which is located the secondary nozzle 7.

The primary nozzle 4 opens or projects into the lower end of the Venturi tube 8, which is preferably removably inserted and held in place by a suitable screw 9, thereby providing for a change in the size or diameter of the Venturi tube, according to the conditions or requirements of the engine. The upper end of the Venturi tube 8 extends into a cylindrical mixing chamber 10, in which the throttle valve is mounted.

The primary nozzle 4 opens or projects into the lower end of the Venturi tube 8, which is preferably removably inserted and held in place by a suitable screw 9, thereby providing for a change in the size or diameter of the Venturi tube, according to the conditions or requirements of the engine. The upper end of the Venturi tube 8 extends into a cylindrical mixing chamber 10, in which the throttle valve is mounted.

In my improved carburetor, as will be seen in Figs. 1 and 3 the throttle valve is of the type known as centrally opening, in that the opening between the valve members takes place central or axially of the mixing chamber 10 and thus completely eliminates any possibility of deflecting the mixture to the walls of the passage, (as is done by the common butterfly valve), the mixture being always retained centrally thereof. In my improved centrally opening throttle valve two cooperating members are used, each member preferably comprising a cylindrical portion 11 provided with trunnions 12, the two cylindrical members being mounted in bored-out cavities in the head 13. A plate 14 is provided for closing the bore opening on the side of the head 13, the plate being secured thereto by screws 15, so that it may be removed for the insertion or removal of the valve members 11. The valve members 11-12 are preferably provided with semicylindrical recesses 16, in the periphery of the cylindrical portions 11 and extending substantially to the axes of the respective cylinders. These recesses are adapted to register when mounted in the casing or head 13, to form the valve opening when the cylindrical valve members are rotated out of the closed position shown by the upper valve of Fig. 1, and toward the position shown by the lower valve in Fig. 1, where the valve members are shown with the valve fully open.

The two cylindrical valve members 11 with their trunnions 12 are preferably formed hollow by being stamped of sheet metal in two halves which are secured together by brazing or welding, as indicated by the diametral lines in Fig. 1. It will be seen that, from this construction, the two halves of the cylindrical members may be stamped or drawn of sheet metal in the same die, the two halves being substantially as indicated by the two halves shown in section in Fig. 2. It will be seen that if one of the half sections in Fig. 2 were turned over onto the other, they would form the complete cylindrical member with the semi-cylindrical recess and this illustrates substantially the way the members are made.

It will be seen that the hollow cylindrical construction of the valve members not only represents a saving of metal and a lightening of the valve members, but enables me to 5 heat the respective valve members by passing hot exhaust gases therethrough as more fully described hereinafter. The cylindrical members 11 of the valve are mounted so that the cylindrical surfaces will be substantially in contact, as shown by the upper 10 valve in Fig. 1 of the drawings, thereby cutting off the passage therebetween of any mixture. It will be seen, however, that by rotating the valve members in opposite directions, the cylindrical recesses 16 will come 15 into register, first with a narrow opening, which will increase in size as the cylindrical members are rotated until they have been rotated a quarter turn each, in which position the valve will be fully open as indicated 20 by the lower valve in Fig. 1 of the drawings. It will be seen that, at all times, the valve opening will be central or axial of the mixing chamber. In order that the two valve 25 members may be rotated simultaneously in opposite directions, they are preferably geared together, by suitable gears 17, which intermesh as indicated in Fig. 2 of the drawings. One of the trunnions 12 of each pair 30 of valve members is provided with a crank arm 18 secured thereto by clamping the split end of the arm by means of a suitable screw 19. The crank arm 18, adjacent the trunnion 12 is provided with laterally extending 35 arms or lugs 20, each provided with a screw 21 adapted to cooperate with a vertical rib 22 projecting from the plate 14 or from the wall of the valve head 13, as indicated in Fig. 3, for limiting the rotative movement 40 of the arms 18 to one quarter of a turn and for adjusting the point of closing of the valve, so that when desired, a small crack or opening may be left for idling the engine.

In the two throttle valve carburetor, as 45 shown in Fig. 1 of the drawings, it will be obvious that either the upper or lower throttle may be connected with the usual manual control and the other throttle connected with a governor. The throttle connected with the governor will be proportionately closed according to the speed of 50 the engine. This particular type of carburetor is therefore, adapted for use in connection with trucks where it is desired to limit the speed. When the engine is at rest, 55 or idling, the governor throttle may be so adjusted as to be wide open, as indicated by the position of the lower throttle in Fig. 1 of the drawings, and adapted to be rotated 60 toward the closed position as the speed of the engine increases. The upper throttle in this view is shown completely closed, but as previously stated, if desired, the position of the crank arm 18 may be varied, so that it 65 will be impossible to completely close the

valve or move the members to the fully closed position shown in Figs. 1 and 3.

A carburetor with a single centrally opening throttle valve is indicated by the broken away upper portion in Fig. 3 of the drawings, the valve corresponding in position to the lower set of valve members shown in Fig. 1, and no further explanation will be necessary for the single throttle valve is constructed and operated in exactly the same manner as either of the valves shown in Fig. 1. The corresponding parts are given the same reference characters.

A further improvement of my carburetor relates to the admission of heated air to the carburetor. In carburetors of this form, provided with primary and secondary nozzles, it is usual to have separate inlet openings for each nozzle, the inlet opening for the auxiliary air being controlled by a valve under spring tension, so adjusted as to open when the vacuum pressure within the carburetor reaches a predetermined point. In my improved carburetor, the primary air passes through the conduit 23 and up past the primary nozzle 4 and through the venturi 8 to the mixing chamber 10. The secondary air passes over the secondary nozzle 7 in the secondary air conduit 24, which, as will be seen from Fig. 1 of the drawings, 95 enters the mixing chamber 10 where both primary and secondary mixtures are united, and the flow thereof controlled by the centrally opening throttle valve. The secondary air conduit 24 is preferably formed or connected as a branch of the primary air conduit through an opening 25, which is provided with a valve 26, adapted to be seated thereon, under tension of a suitable spring 27. The auxiliary air chamber 24, 100 above the valve 26, may preferably be provided with an opening or hand hole 28 for access to the inner wall of the conduit when forming the valve seat and for properly inserting the valve in place. The opening 28 is closed by a cap 29, in which an adjusting nut 30 is screw threaded, a lock nut 31 being provided for holding the nut 30 in any adjusted position. The valve 26 is provided with valve rod or stem 32, extending 110 upward through a hole in the adjustable cap screw 30, the adjustable screw 30 being thereby adapted for adjusting the tension on the spring 27. In this manner, it will be seen that the vacuum pressure at which the 115 valve 26 will open can be varied as required.

The valve rod 32 is reduced in size at 33, where the valve is attached thereto by crimping or spinning the metal into the groove thus formed. The lower end 34 of the rod 125 extends below the valve and through a bushing 35 screwed into the lower wall of the primary air conduit, substantially as indicated in Fig. 1 of the drawings. A lock nut 36 may be provided for holding the 130

bushing nut 35 in proper place. The lower end of the rod 34 is threaded at 37 and provided with a nut 38 and lock nut 39 cooperating with a secondary spring 40 seated 5 between the nut 38 and the lower turned down end of the bushing nut 35. The spring 40 is adapted to be brought into operation only after the valve has been lifted a predetermined amount, to thereby increase 10 the resistance to lifting and control the auxiliary air passing through the valve. A cap 41 is screwed on to the lower end of the bushing screw 35 for protecting the spring 40 and associated parts. In order 15 that the valve 26 may be more sensitive and operate substantially independent of gravity, it is preferable to provide a spring 42, surrounding the lower valve stem 34 for counter-balancing the weight of the valve. 20 By this construction, it will be seen that the opening of the valve 26 to admit auxiliary air to the secondary nozzle may be controlled by the tension on the spring 27 and the tension on the spring 27 may be varied by 25 adjusting the cap nut 30, as previously indicated. The point at which the secondary spring 40 comes into action may be varied by adjusting the nuts 38 and 39, as will be readily understood from an inspection of 30 the drawings.

The primary and secondary or auxiliary air is adapted to be drawn through a single tubular conduit 43, which is preferably provided with the usual choke valve 44, which 35 may be brought into operation when starting the motor in the usual manner. In my improved construction, however, it will be seen that the choke valve automatically controls the auxiliary valve 26 and the latter is 40 prevented from opening when starting the engine because the vacuum pressure is the same on both sides of the valve 26 and there will be no tendency for the valve to open. The pipe 43 forming the single conduit 45 opening for supplying both primary and auxiliary air to the carburetor may be connected in the usual manner by means of flexible metal tubing (not shown) with a suitable supply of highly heated air. This 50 construction has the advantage of providing heated air of the same temperature for both the primary and auxiliary conduits through the carburetor.

In carrying out my improvement for heating the throttle valve members, it will 55 readily be understood that a flexible metal pipe or other suitable means may be connected with the exhaust pipe or manifold of the engine and arranged to conduct exhaust 60 gases through a T-shaped tubular bracket 47 secured to the rear face of the carburetor valve head 13 by suitable screws 48, as indicated in Fig. 2. The exhaust gases will enter the branching tube through the opening 49, and dividing will pass, as indicated

by the arrows in Fig. 2, through the trunnions 12 of the respective cylindrical valve members 11, and out through the opposite trunnions 12. The bracket 47 is provided with two holes adapted to surround the respective trunnions 12 and counterbores are provided at 50, for engaging the bearing bosses 51, in which the trunnions 12 rotate. By this construction, it will be seen that a tight joint will be formed between the casing 75 13 and the T-shaped tubular member 47, through which the exhaust gases are adapted to pass and yet the valve members 11 will be free to rotate on their trunnions 12. The hot exhaust gases passing through the tubular valve members 11 will strike the inner walls of the semi-cylindrical valve opening surfaces 16 and heat the latter. When the valve members are in partially open position, it will be seen that a larger proportion 80 of the heated valve area will be exposed to the impact of the mixture than when the valve is fully opened. This is desirable in that at full opening, the amount of heat required under certain conditions may not be 85 as great as when the valve is partially open. 90

It will be understood that while I have shown the preferred form of my improved carburetor, and the centrally opening heated throttle valves, I do not wish to be limited 95 to the specific construction shown and described, for various modifications in the adaptation of the valves and the heating thereof, as well as in the construction of the auxiliary air valve, may be made without departing from the spirit and scope of the invention. 100

I claim:

1. In a carburetor wherein the fuel and air are mixed in a mixing chamber located above the nozzle, a centrally opening throttle valve at the outlet of the mixing chamber, comprising a pair of valve members formed as hollow cylinders with hollow trunnions and mounted in parallel relation so that adjacent faces of the cylinders contact, said cylinders being indented transversely of their axes with semi-cylindrical recesses adapted to form the throttle valve opening, and means cooperating with said hollow trunnions for passing hot exhaust gases 110 through both valve members, the arrangement being such that at partially open throttle the mixture passing therethrough is sheeted and heated on both sides. 115

2. In a carburetor, wherein the fuel and air are mixed in two successive mixing chambers located above the nozzle, centrally opening throttle valves at the outlets of the successive mixing chambers, through which the mixture is adapted to pass in succession, each throttle valve comprising a pair of valve members formed of hollow cylinders with hollow trunnions, said cylinders being indented transversely of their axes with re- 125 130

cesses adapted to cooperate and form the valve opening, and means associated with the respective trunnions for passing hot exhaust gases through the valve members of both valves for heating the same, the mixing chamber between said throttle valves being adapted to provide an expansion chamber

for agitating the mixture after being heated by passing the first valve, the arrangement being such that the two valves under normal 10 operation are adapted to successively sheet and heat the mixture in stages.

WILLIAM E. S. STRONG.
